US00D844458S

(12) **United States Design Patent** (10) Patent No.: **US D844,458 S**
(45) Date of Patent: ** Apr. 2, 2019

(54) **WATCH WITH DISPLAY**

(71) Applicant: **Garmin Switzerland GmbH**,
Schaffhausen (CH)

(72) Inventors: **Robert S. Lillquist**, Lenexa, KS (US);
Wei-Hao Lian, New Taipei (TW);
Jin-Ming Chen, New Taipei (TW)

(73) Assignee: **Garmin Switzerland GmbH** (CH)

(**) Term: **15 Years**

(21) Appl. No.: **29/609,882**

(22) Filed: **Jul. 6, 2017**

(51) LOC (11) Cl. **10-02**

(52) U.S. Cl.

USPC **D10/30**

(57) **CLAIM**

The ornamental design for a watch with display, as shown and described.

DESCRIPTION

FIG. 1 is a front perspective view of a watch with display according to the present invention;

FIG. 2 is a rear perspective view of the watch with display;

FIG. 3 is a top view of the watch with display;

FIG. 4 is a front view of the watch with display;

FIG. 5 is a bottom view of the watch with display;

FIG. 6 is a rear view of the watch with display;

FIG. 7 is a left side view of the watch with display; and,

FIG. 8 is a right side view of the watch with display.

The broken lines shown in the drawings represent portions of the watch that form no part of the claimed design.

1 Claim, 4 Drawing Sheets
